UNITED STATES PATENT OFFICE.

LOUIS COTÉ, OF ST. HYACINTHE, QUEBEC, CANADA.

HEEL-COUNTER.

SPECIFICATION forming part of Letters Patent No. 350,618, dated October 12, 1886.

Original application filed June 29, 1885, Serial No. 170,125. Divided and this application filed January 30, 1886. Serial No. 190,371.
(No model.)

To all whom it may concern:

Be it known that I, LOUIS COTÉ, of the city of St. Hyacinthe, in the county of St. Hyacinthe, Province of Quebec, Canada, have invented new and useful Improvements in Heel-Counters; and I do hereby declare that the following is a full, clear, and exact description of the same.

I would in the first place state that the present invention is a subdivision of the subject-matter of the application for a patent, Serial No. 170,125, filed June 29, 1885, and for which Letters Patent have been granted to me on the 11th day of May, 1886, under No. 341,459.

This invention has reference to the production of heel-counters, similar but being an improvement upon those counters a patent for the mechanism for forming which was granted me on the 19th day of June, 1883, under No. 279,717.

I will first describe my improved counter forming the present invention, and afterward a mechanism suitable for forming my said improved counter.

In the drawings hereunto annexed, similar letters of reference indicate like parts, and Figure 1 is a side elevation, part in section, of a mechanism suitable for forming my improved counters. Fig. 2 is an end elevation of the mechanism shown in Fig. 1. Fig. 3 is a diagram of the old method of arranging the mechanism heretofore in use. Fig. 4 is a diagram of a heel-counter. Fig. 5 is a plan of a piece of stock cut to the desired shape to form a counter. Fig. 6 is a diagram illustrating an endeavor which has been made to overcome the objections existing in the old counters, which objections are removed from the present counters. Fig. 7 is a diagram showing the effect of the stretching of the material at the edge M.

Heretofore a piece of material cut to the configuration shown in Fig. 5, after its bottom edge, O, had been crimped in the ordinary manner, was passed between a revolving spherical former, D, and a corresponding stationary mold, E, the said former and mold being situated in relation to one another, as shown in Fig. 3—that is to say, with a space, F, between them, which space F was equal on the side H to that on the side G. The piece of stock shown in Fig. 5 being passed longitudinally through the space F, the piece of stock was compressed and

rolled equally all over and brought to the configuration of a counter similar to that shown in Fig. 4, taking the dotted line K as the forming part of its outline.

Many or most of the counters formed as just above mentioned were found to have a number of wrinkles (indicated by the dotted lines J) at the back of the heel-counter and at the upper edge thereof, thus weakening the counter. It was also found that the counters were too much contracted at the back upper part, as indicated by the dotted line K, whereas to properly fit the heels they should have the configuration given to them indicated by the solid line L. Various experiments were made to overcome these objections, one of which was to cut the pieces of stock out of which the counters were formed to the configuration shown in Fig. 6, instead of Fig. 5. The configuration shown in Fig. 6 was not only more trouble to crimp the lower edge of, on account of its not being straight, but it also consumed more stock to form a counter; also, this did not remove the objection before referred to, of the wrinkles at J and the undue contraction indicated by the dotted line K.

I will now describe the arrangement and action of the mechanism shown in Figs. 1 and 2, by the use of which my improved heel-counters are formed.

A is any suitable frame, in which is carried by journals B in bearings C' a revolving shaft, C. One only of the journals B and bearings C' is shown. On the shaft C is secured a former, D, similar to those heretofore in use. E is a mold similar to those heretofore in use, and set in relation with the former D, as heretofore in use, and shown in Fig. 3, with the exception that instead of the recess of the mold being set concentric with the former D it is set eccentrically or unevenly, so that the space F, instead of being a parallel or equal one, as shown in Fig. 3, is now an unequal one, being narrower at one side than the other, as shown. The side at N is considerably smaller than the side at P. The amount of this uneven setting of the former and mold, or amount of inequality of the space F, will depend upon the thickness and nature of the material to be formed into counters; but it must be such as to have the desired effect upon the material, and this effect I will now describe. The piece of material

shown in Fig. 5 being passed longitudinally between the former and mold shown in Fig. 1, is so placed that the edge M will pass through the narrower part N of the space F, while the edge O will pass through the wider part P of the space F. By the proper relative placing of the position of the former and mold the one to the other the effect produced on the piece of stock shown in Fig. 5 will not only be to curl or form it into shape, but also to roll with such force as to permanently stretch that portion of the stock adjacent to the edge M in the center part of the counter, or, say approximately the part of the material about and above the line α in Fig. 5. The action of extending the material beginning at or about the line α in Fig. 5, which line will be situated according to the shape of counter required, gradually the higher and nearer we come to the edge M, by which gradual increase extension of the material the hereinbefore-mentioned desired effect is produced without forming any creases or ridges upon the surfaces of the counters.

The counters forming the present invention may be readily distinguished from those made in the manner or by the means heretofore in use, because by measuring the thickness of the material at the center of the upper part of the edge M, and comparing it with the thickness of the material at or about the line α , it will be found that the material is thinner at M than at the line α , and this is one criterion for showing the difference between the counters heretofore

made and those of the present invention. As another and unfailing criterion by which the real and substantial difference in the counters made according to the present invention differ from those made heretofore can be seen, is that if the counters heretofore made be taken and damped and flattened out they will return to the same configuration that the piece of material had or was cut to before it was pressed into the shape of a counter, while the counters made according to the present invention will come substantially (more or less) to the form shown by solid lines in Fig. 7, instead of coming to the form shown by dotted lines in that figure, which is the shape the piece of material out of which it was formed was cut to, showing clearly that in the one case the material has been permanently stretched at the edge M, and in the other case that it has not.

I am aware that it is not new to cut a piece of material to shape and press it into the form of a counter.

What I claim is as follows:

An improved article of manufacture, a boot or shoe heel counter, substantially as shown, having its upper part, or that part of it lying between the upper edge, M, and line α , permanently compressed and extended, substantially as described, for the purposes set forth

LOUIS COTÉ.
